Frank A. Neel

UNITED STATES PATENT OFFICE.

WILLIAM G. WHITELEY, OF BOONTON, NEW JERSEY.

TOY.

Application filed October 6, 1921. Serial No. 505,698.

To all whom it may concern:

Be it known that WILLIAM G. WHITELEY, a citizen of the United States, residing at Boonton, in the county of Morris and State 5 of New Jersey, have invented certain new and useful Improvements in Toys, of which the following is a specification, reference being had therein to the accompanying drawing.

10 My invention relates to improvements in toys, and more particularly has reference to a disc or dial having characters such as figures, and provided with a movable hand, pointer, or indicator for disclosing 15 said characters when the disc or hand is rotated, one relative to the other, and more particularly is intended for and adapted for use in combination with a wire structure formed as a top or jack, more particu- 20 larly set forth in my co-pending patent application 445,313, filed Feb. 16, 1921.

Referring to the accompanying drawings, Fig. 1 illustrates in perspective, parts being broken away, a suitable form of disc 25 designed as a dial upon a top or jack structure such as referred to, and shows the hands or pointers in position thereon, part of the disc being broken away. Fig. 2 is an enlargement of the same in plan view. 30 Fig. 3 is a cross-section on the line 3—3 of Fig. 2, looking from left to right there- at. Fig. 4 is a plan view of a suitable form of dial with the other parts eliminated. Fig. 5 is an enlarged side elevation of the 35 eyelet or shank passing through the centre of the dial, and upon which the hands are mounted, and Fig. 6 is an enlarged plan view of one of the hands or pointers.

7 indicates the wire structure which may

be used as a top or jack and as illustrated 40 in my said co-pending patent application, and 8 is the shank or spinning handle thereof. 9 indicates an eyelet upon which the disc such as 10, and hands or pointers such as 11—12, may be rotatably secured as 45 shown, the hole 13 of the eyelet being large enough to pass freely over the spinning shank 8, from which it will be seen that when the top is spun, the disc or dial and the hands are each shifted in the act of 50 spinning so that when the top comes to rest a different reading will be indicated upon the dial each time the top is spun. In this way a child using the device as a top may be taught to read the time, or by 55 variations in the characters of the dial may be taught to read or discern other facts as may be found desirable.

Of course it will be understood that various modifications may be made in the construction and arrangement of parts without departing from the spirit of the invention 60 as claimed.

I claim:

In a toy of the class described, an integral wire structure adapted to be spun as a top, the spinning point of the same being formed at one end of said wire, and the finger portion of said top being formed at the other end of said wire, a dial mem- 70 ber adapted to be retained upon said finger portion, an indicator member also adapted to be retained upon said finger portion over said dial, and one of said members rotatable independently of said structure. 75

In testimony whereof I hereunto affix my signature.

WILLIAM G. WHITELEY.
